United States Patent Office.

PETER BARRY, OF NEWARK, NEW JERSEY.

Letters Patent No. 96,381, dated November 2, 1869.

IMPROVEMENT IN MACHINE FOR WIRING BLIND-SLATS, &c.

The Schedule referred to in these Letters Patent and making part of the same.

To all whom it may concern:

Be it known that I, PETER BARRY, of Newark, in the county of Essex, State of New Jersey, have invented a new and improved Machine for Wiring Blind-Slats and Rods; and I do hereby declare the following to be a full, clear, and exact description thereof, which will enable those skilled in the art to make and use the same, reference being had to the accompanying drawing, forming part of this specification, in which drawing—

Figure 1 represents a sectional front view of this invention.

Figure 2 is a horizontal section of the same.

Figure 3 is a transverse vertical section of the same. Similar letters indicate corresponding parts.

This invention consists in the arrangement of two cut-off jaws, bearing on the staples from opposite sides, and provided with a recess, in combination with the feed-guide and the plunger, in such a manner that, whenever the plunger is raised above the cut-off jaws, the foremost staple is permitted to drop into the recess of the cut-off jaws under the plunger, and when the plunger is depressed, said staple is carried down and driven into the slot or rod below, and at the same time, by the action of the plunger, the cut-off jaws are opened to allow the staples to slide down on the feed-guide, and to bring the succeeding staple in position to be carried into the machine by the subsequent stroke of the plunger.

The invention consists, further, in the arrangement of a toothed segment gearing into a rack connected to the plunger, and also into a rack carrying the feed-pawl for the rack used in wiring blind-rods, in combination with a hand-lever connected to the plunger in such a manner that the motion of the hand-lever and plunger is transmitted by a simple and efficient mechanism to the feed-pawl.

An adjusting-screw, under the feed pawl, serves to regulate the feed-motion of the rack carrying the blind-rod.

In the drawing—

The letter A designates a bed-plate, from which rises a slotted standard, B, to which is secured the frame C, that supports the working-parts of my wiring-machine, said frame being attached to the standard B by a set-screw, a, so that it can be readily adjusted up or down, according to the work to be accomplished.

The frame C is provided with a slot, b, which forms the guide for a head, c, that carries the plunger D, and the head c connects, by a pivot, d, with a hand-lever, F, which is pivoted to the frame C, so that by its action a rising-and-falling motion can be imparted to the head c and plunger D.

The staples to be inserted into the blind-slats or

rods are placed on an inclined feed-guide, E, which is attached to the lower part of the frame C, having a throat, d', through which one staple after the other is forced down by the action of the plunger.

On the sides of the feed-guide E are situated the cut-off jaws e, the inner surfaces of which are roughened, so that they are capable of retaining the staples, and said jaws are provided with recesses f on their inner edges, (see fig. 3,) so that one staple after the other, after having passed through between the roughened surfaces, is enabled to drop down under the plunger in the throat d'.

The plunger increases in width toward its head, and as the same is forced down between the cut-off jaws, it opens the same, and allows the first or lowest staple in the row to drop into the recess f, where it rests against the front side of the plunger, until said plunger is raised high enough to allow the staple to drop under it and into the throat d', while the cut-off jaws close by the action of springs g, (see fig. 2,) inserted behind them as soon as the plunger rises, and thereby the row of staples on the feed-guide is retained and prevented from dropping down against the plunger.

The springs g, shown in the drawing, are simple pieces of India rubber, but springs of any other construction might be used.

The staple which drops into the throat d' is retained therein by the friction-spring h (see fig. 3) until the plunger descends and drives it down into the slot or rod below.

By this arrangement the staples are fed to the throat automatically and in single succession without fail, and the operation of driving them into the blind-slats or rods can be performed with great rapidity.

From the head of the plunger D extends an L-shaped arm, G, the edge of which forms a toothed rack, p, that gears into a segment, q, mounted on a pivot, r, which is secured in the frame C.

Said segment also gears into a sliding rack, H, which is supported by a lip or rail projecting from the frame C, and which is guided in a slot, s.

To this rack is attached the pawl t, which is intended to feed the rack carrying the blind-rods, into which the wires or staples are to be inserted.

The amount of feed-motion produced by this pawl is adjusted by a screw, u, which permits said pawl to catch into the teeth of the feed-rack sooner or later, according to its position.

If said screw is turned back, the pawl t produces a greater feed than it does if said screw is turned forward.

When blind-slats are inserted into my machine, the pawl t is thrown back, no feed-rack being required in this case.

Having thus described my invention,

What I claim as new, and desire to secure by Letters Patent, is—

1. The cut-off jaws *e*, provided with recesses *f*, in combination with the feed-guide *E* and tapering plunger *D*, substantially as set forth.

2. The vertical rack *p*, secured to the slide *c*, which carries the plunger *D*, in combination with the segment *q*, and horizontal rack *H*, carrying the pawl *t*, when the parts are combined and arranged to operate together, as described.

3. The arrangement of the jaws *e*, feed-guide *E*, tapering plunger *D*, racks *p H*, segment *q*, feed-pawl *t*, and screw *u*, substantially as and for the purpose described.

PETER BARRY.
